[57] CLAIM

The ornamental design for a vehicle roof mounted air reversing unit, as shown and described.

DESCRIPTION

FIG. 1 is a side elevation view of a vehicle roof mounted air reversing unit showing my new design, the opposite side being a mirror image thereof, it being understood that the broken lines are for illustrative purposes only and form no part of the claimed design; FIG. 2 is a front elevation view thereof; FIG. 3 is a bottom plan view thereof; FIG. 4 is a rear elevation view thereof; FIG. 5 is a top plan view thereof; FIG. 6 is an isometric view of the top, front and one side thereof; and FIG. 7 is an isometric view of the top, rear and one side thereof.
